UNITED STATES PATENT OFFICE.

MARTIN M. HANSON, OF CLEARWATER, NEBRASKA.

REVOLUBLE VALVE FOR INTERNAL-COMBUSTION MOTORS.

1,274,100.

Specification of Letters Patent. Patented July 30, 1918.

Application filed September 22, 1917. Serial No. 192,711.

To all whom it may concern:

Be it known that I, MARTIN M. HANSON, a citizen of the United States, residing at Clearwater, in the county of Antelope, State of Nebraska, have invented a new and useful Revoluble Valve for Internal-Combustion Motors; and I do hereby declare the following to be a full, clear, and exact description of the invention, such as will enable others skilled in the art to which it appertains to make and use the same.

This invention relates to the art of internal combustion motors or engines, and particularly to a revoluble valve therefor, whereby the intake of the charges and the exhaust of the utilized gases for a multiple of cylinders may be controlled.

One of the objects of the invention is to provide a motor revoluble valve, thereby dispensing with cam shafts, puppet valves, springs, valve seats, valve stems, adjusting nuts, and all other noise attachments and troublesome devices.

A further object of the invention is to provide a revoluble motor valve, which is an improvement over the so-called motor sleeve valve, thereby dispensing with the eccentric shaft, the inner and outer sleeves, connecting rods and junk rings, and thereby providing a motor revoluble valve, which is durable, positive, and which is constructed of few parts, thereby enabling a motor revoluble valve of this kind to be constructed or manufactured for a small cost and sold at a reasonable profit.

A further object of the invention is to provide a multiple cylinder motor having a revoluble cylindrical tubular valve provided with a multiple of intake and exhaust ports for controlling the intake of the charges and the exhaust of the utilized gases into and from the cylinders, said valve being given a positive drive by means of a noiseless chain or gear mechanism from the crank shaft, said mechanism being timed four to one. For instance, said valve is designed to be given one eighth turn to each upward and downward stroke of the piston, or one fourth turn to each turn of the crank shaft.

A further object involved by the provision of the improved motor revoluble valve is the elimination of wear on the several parts of the valve mechanism, in fact, owing to the construction of the valve the wear is reduced to a minimum.

A further object of the invention is to pro-

vide a valve of this kind which is positively impervious to air or gas, thereby insuring flexibility of the operating parts, long service, increasing power, and lowering the cost of construction, as well as insuring quietness, as well as simplicity, lessening the cost of operation, and also reducing carbon troubles.

In practical fields the details of construction may necessitate alterations falling within the scope of what is claimed.

The invention comprises further features and combination of parts as hereinafter set forth shown in the drawings and claimed.

In the drawings:—

Figure 1 is a view in elevation of the upper portions of the cylinders of a multiple cylinder internal combustion motor, showing the revoluble valve as applied thereto.

Fig. 2 is a longitudinal sectional view through the valve structure, showing the multiple cylinder motor in elevation in the rear.

Fig. 3 is a sectional view on line 3—3 of Fig. 2, showing the exhaust port of the cylinder closed, and a transverse intake passage of the valve in registration with the intake port of the cylinder.

Fig. 4 is a view similar to Fig. 3, also showing the exhaust port closed and the intake passage of the valve out of registration with the intake port of the cylinder, consequently the piston (not shown) of the cylinder is on its compression stroke.

Fig. 5 is a sectional view similar to Figs. 3 and 4, the exhaust ports still closed, as well as the intake port, since the intake and exhaust passages of the valve are still out of registration therewith, consequently the piston (not shown) of the cylinder is on its explosion or working stroke.

Fig. 6 is a sectional view similar to Figs. 3, 4 and 5, showing the exhaust port open and the intake port still closed, in which case the piston (not shown) of the cylinder is on its exhaust stroke, thus it will be seen by reference to the previous figures that the valve has made one half a revolution to two complete revolutions of the crank shaft (not shown) of the engine.

Figs. 7, 8, 9, and 10 are views similar to Figs. 3, 4, 5 and 6 showing the same relative positions of the valve as previously disclosed in Figs. 3 to 6 inclusive, but conveying the fact that said valve has moved its other half revolution to two more complete

revolutions of the crank shaft (not shown), in which case it will be observed that the crank shaft makes four complete revolutions to one revolution of said valve.

5 Fig. 11 is a longitudinal section of a part of the valve.

Referring more especially to the drawings, *a*, *b*, *c* and *d* designate the multiple of cylinders of the motor, and as shown in 10 Figs. 1 to 10 inclusive said cylinders are constructed with double walls 1 and 2, spaced, whereby a water jacket 3 is constructed. The cylinders are arranged in parallel, and in consecutive order as designated. The 15 corresponding portions of the outer walls of said cylinders are provided with semi-cylindrical bearings 4, and the inner portions of these bearings have hollow or tubular connections 5 with the inner wall of said cylinder, and by means of the hollows or passages 20 of said connections 5 exhaust and intake ports 6 and 7 are provided for the cylinders. A revolute cylindrical valve 8 is mounted in the bearing 4 and is constructed tubular, 25 and diametrically opposite portions thereof are provided with a multiple of intake and exhaust openings 9 and 10, and transverse tubes 11 rectangular in cross section connect the diametrically opposite portion of the 30 valve adjacent the openings, said tubes having intake and exhaust passages 12 and 13, which are designed to register with the intake and exhaust ports 6 and 7. In order to hold the valve in its bearing 4 a semi-35 cylindrical cover plate 14 arches over the valve cylinder, and is provided with flanges 15. Suitable screw bolts 16 are threaded through the flanges 15 and into the outer wall 2 of the cylinders of the motor, thereby 40 securing the cover plate in place. The cover plate is provided with a plurality of intake and exhaust ports 17 and 18, which are designed to be registered with by the intake and exhaust passages 12 and 13. The cylindrical valve 8 between the intake and 45 exhaust openings 9 and 10 is provided with annular grooves or recesses 19, arranged in pairs and having suitable packing rings 20 therein, to insure against leakage of the 50 charges. One end of the cylindrical valve has an integral collar 21 and which end is closed as shown at 22. This collar 21 engages the corresponding ends of the bearing 4 and the cover plate 14, thereby preventing 55 axial movement of the valve in one direction. The end 22 is closed, owing to the provision of an axial extension 23, which is provided with a suitable sprocket 24, which, by means of a noiseless chain 25 may 60 be geared to the crank shaft (not shown) of the motor, said gearing to be so constructed, that the cylindrical valve will make one complete revolution to every four complete revolutions of the crank shaft. If desired 65 gears may be substituted for the noiseless

chain drive. The other end 26 of the valve is extended, and has secured thereon by means of the screws or the like 27 a collar or ring 28, which engages the corresponding end of the bearing 4 and the cover plate 14, 70 in order to prevent axial movement of the valve in the opposite direction.

Referring to the cylinder *a*, the operation will be understood as follows; particularly when tracing the positions of the valve as 75 shown in Figs. 3 to 10 inclusive. When the valve is in the position shown in Fig. 3 the piston of cylinder *a* is on its intake stroke, the passage 12 is in registration with the openings or ports 7 and 17, while the passage 13 is out of registration with the ports or openings 6 and 18. As the crank (not shown) moves the piston on its down stroke the valve 8 is moved to the position shown in Fig. 4, then the crank will start moving 80 the piston (not shown) on its compression stroke, and while the valve is in the position shown in Fig. 5, the piston (not shown) is on its explosion or working stroke. The piston (not shown) then moves upwardly, 85 consequently making two complete revolutions of the crank shaft (not shown), bringing the valve to the position shown in Fig. 6, hence exhausting the utilized gases, said valve having made one half revolution. By 90 referring to Figs. 7 to 10 inclusive, it will be seen that the same cycles of the valve and the piston are repeated, the valve making another half revolution to two complete revolutions of the crank shaft (not shown), 95 consequently completing a full revolution of the valve to four revolutions of the crank shaft. The same operation of the valve with relation to the cylinders *b*, *c* and *d* are 100 performed. However, it is to be understood that should the valve and its passages 12 and 13 be constructed, in order to permit the intake and exhaust of the charges of the several cylinders to alternate in such wise that only one cylinder at a time will be exploded, said structure will fall within the 105 right of the inventor.

The invention having been set forth what is claimed as new and useful is:—

1. In an internal combustion motor, a casing having a multiple of combustion chambers, the end and cylindrical walls of each chamber comprising inner and outer thicknesses and a water space between said thicknesses, the outer thicknesses of said walls of the chambers having an elongated bearing semi-cylindrical in cross section extending transversely of the casing and off-set to one side of the chambers, the inner part of said semi-cylindrical bearing having at intervals 115 integral connections with the respective inner thicknesses of the walls of said multiple of chambers, a semi-cylindrical cover plate arching said bearing and being secured to the outer thicknesses of said multiple chambers 120

ber walls, thereby forming an elongated transversely disposed cylindrical bearing, said semi-cylindrical bearing having intake and exhaust ports with said chambers 5 formed through said integral connection with the inner walls of said chambers, said cover plate having intake and exhaust ports diametrically opposed to the first intake and exhaust ports and adapted for communication 10 to the intake and exhaust manifolds, a cylindrical tubular valve closed at one end and open at the other mounted in said cylindrical bearing, said valve being provided with transversely disposed intake and exhaust 15 passages at angles to each other and having their opposite ends adapted to register with the diametrically opposed intake and exhaust ports of the semi-cylindrical bearings and said cover plate on every half 20 revolution of said valve, means to rotate the valve a complete revolution to every four complete revolutions of the engine crank shaft, and means at the opposite ends of said valves to prevent axial movement of the 25 same.

2. In an internal combustion motor, a multiple cylinder casing having a multiple of combustion chambers, the cylindrical walls of said chambers comprising inner 30 and outer thicknesses, a valve bearing comprising a semi-cylindrical wall connecting the outer thicknesses of the walls of said chambers at corresponding points, said semi-cylindrical wall of the valve bearing at cor-

responding points integrally connecting the 35 inner thicknesses of the walls of said chambers, said integral connections with the inner thicknesses having intake and exhaust ports therethrough and in communication with said chambers, a cover plate arching 40 a valve in said bearing to retain the valve in place, said cover plate having intake and exhaust ports diametrically opposed to the intake and exhaust ports of said integral connections, a cylindrical valve in said bearing 45 and provided with intake and exhaust ports at angles to each other and having their opposite ends adapted to register with the diametrically opposed intake and exhaust ports of the bearing and the cover plate on every 50 half revolution of the valve, said valve being tubular and provided with a flanged closed portion at one end to engage one end of the bearing, and a removable ring 55 removably secured to the other end of the valve to coöperate with the other end of the bearing, whereby axial movement of the valve may be avoided, said other end of the valve being open, whereby exterior air may enter the valve to assist in cooling the same. 60

In testimony whereof I have signed my name to this specification in the presence of two subscribing witnesses.

MARTIN M. HANSON.
